[57] **CLAIM**

The ornamental design for a baseball bat shaped bottle opener, as shown and described.

DESCRIPTION

FIG. 1 is a perspective view of a baseball bat shaped bottle opener, showing my new design;

FIG. 2 is a top plan view thereof;

FIG. 3 is a rear elevational view thereof;

FIG. 4 is a left side elevation view thereof, the right side elevational view being a mirror image thereof;

FIG. 5 is a front elevational view thereof; and,

FIG. 6 is a bottom plan view thereof.
